UNITED STATES PATENT OFFICE.

JACK POTTER STOCKTON, OF SPRING LAKE, NEW JERSEY.

AUTOMATIC CONTROL FOR PHONOGRAHS.

Application filed November 1, 1927. Serial No. 230,225.

The present invention relates to automatic controls for phonographs and more particularly relates to devices for stopping a phonograph motor or record support at the termination of the playing of a record, or for initiating the actuation of repeat or record changing mechanism in automatic repeating phonographs.

Most disk type phonographs records now available are provided with sound grooves of uniform pitch spaced about one hundred to the inch, and also have additional grooves inside the playing surface which communicate with the sound grooves to receive the stylus 10 on the reproducer. The stylus is thus carried from the last groove of the playing surface into these special grooves so that the reproducing means is moved accordingly. These grooves have not been standardized by 15 the various manufacturers of phonograph records. They take various forms and sizes according to the fancy of the maker. Some of the manufacturers use grooves which are concentric with the center of the record, while 20 other manufacturers use other grooves which are eccentric with respect to the record center. These concentric grooves are at various radii and the eccentric grooves are of various diameters and are placed at various off center 25 distances from the center of the record.

Inasmuch as the sound grooves are in the form of a spiral about the center of rotation of the record, and are closely spaced to economize in space, it results that the stylus and 30 its support (generally a tone arm) may have a substantially uniform angular movement about the pivot of the support as the stylus is carried in toward the center of the record by the sound grooves. In all cases, the various eccentric or concentric grooves, above 35 referred to, are continuations of the sound groove, so that the stylus passes from the sound groove into the special groove. As these special grooves must be inside the playing surface, it is apparent that the angular movement of the reproducer and support about the pivot of the tone arm will be accelerated as soon as the stylus enters any of these forms of special grooves. The acceleration 40 will of course be dependent upon the pitch of the groove carrying the stylus in toward the center of the record, and the angular extent of the groove having the increased pitch.

The concentric form of special groove in 45 the record has been utilized to actuate or control various automatic stop mechanisms and

switch mechanisms for stopping the phonograph or for initiating the actuation of a repeat mechanism in an automatically repeating phonograph. Others have provided 60 mechanisms for these purposes which operate in response to the outward movement of the stylus and tone arm caused by the eccentric groove.

The present invention contemplates the 65 provision of a mechanism which will function on any or all of these forms of records to actuate the automatic switch or repeat or record changing mechanism after the completion of the playing of a record. With the 70 present mechanism one is able to use a much wider selection of records than is possible where the mechanical features of the phonograph restrict the records to those of a particular manufacturer; for, with the present 75 device the automatic stop and automatic repeat or record change mechanism may function the same on any or all records wherein the stylus and tone arm are moved toward the center of the rotating record at a speed 80 substantially greater than the ordinary inward movement caused by the spiral groove occupying the playing surface.

The records of the various manufacturers, provided, as they are, with these various 85 grooves, normally carry the stylus in toward the center of the record. The point of greatest inward movement of the stylus is a considerable distance from the center pin, and the present invention contemplates that 90 the automatic control device will function whenever the stylus is carried in closer than this position. In a few cases the records may have no special grooves, or the special groove may be poorly formed or worn, so that the 95 stylus refuses to follow it. The present invention provides for such cases as this, and the automatic control functions upon the turn table making a predetermined number of revolutions after the stylus has been brought to 100 a predetermined position. The number of such revolutions is greater than required for the completion of the playing of a record having the most closely placed special groove.

I have discovered that the automatic operation of a control device may be most conveniently obtained by making use of differential action between two members. To obtain this differential action one of the members is connected to the support for the sound 105 reproducing means so as to be moved by it at 110

a speed which is determined by the pitch of the groove in the record support. The other member is so arranged that it may be moved bodily with the first member during part of the movement, thereby permitting the two members to move back and forth with the reproducing means when the reproducing means is within a certain range of its movement. Suitable mechanism is provided, however, for taking up or assuming the drive of the second member when the stylus is brought into the inner part of the record surface. This motor operated drive for the second member is preferably timed so that it will move this member at the same speed that it was moving when under the control of the stylus. In this manner the two members may be moved at the same speed and will maintain the same relative position even though one is being moved by the stylus and the other is being operated from the motor by suitable mechanism. As, however, the speed of this second member is then dependent upon the motor speed, it will be apparent that it will remain relatively stationary with respect to the first member until this first member is given a sudden impulse due to an increase of pitch in the record groove. While various mechanisms may be employed for bringing about this differential movement, a simple form of mechanism for the purpose may preferably include a stationary motor driven worm and a follower for the worm carried on or supported by the second member above referred to.

Where the present invention is intended for controlling either the turn table motor or the auxiliary motor of the automatic record change or repeat mechanism, suitable electric switching connections may be carried by the swinging member and interconnected with the follower for the worm so as to be opened or closed as the case may be whenever the differential movement takes place.

The invention also contemplates the automatic resetting of all the parts when the tone arm or reproducer support is swung back toward the initial position to begin playing a record. This is preferably accomplished by a suitable arrangement of stops, links, and interlocking connections so that the parts are re-set in position to again function automatically. The invention also contemplates the provision of a limit stop which will actuate the control device whenever the sound reproducing means is swung beyond a predetermined position, and also the provision of a manually operated means for actuating the device at any time.

The invention is capable of being embodied in a number of mechanical forms, one of which is shown in the accompanying drawings together with such modifications as to show adaptations of the invention for carrying out the various purposes above referred

to, it being especially understood that the drawings are for the purpose of illustration only and are not to be construed as a definition of the limits of the invention.

In these drawings:

Figure 1 is a top plan view of a phonograph showing the turn table, tone arm and automatic control arranged for controlling the turn table motor;

Figure 2 is a top plan view of the control device showing in full lines the position which it assumes during the playing of an early portion of the record and in dot and dash lines the position which it assumes during the playing of the later portions of the record;

Figure 3 is a fragmentary sectional view taken on the line 3 of Figure 2 in the direction of the arrow and showing the circuit for the turn table motor closed;

Figure 4 is a fragmentary view showing the position of the parts when the stylus is traversing the portion of the record of greater pitch and just prior to the release of the trip;

Figure 5 is a view similar to Figure 2 showing in full lines the position the parts assume after the actuation of the trip mechanism, and in dot and dash lines the position of the parts just before they are reset by the return movement of the reproducing means;

Figure 6 is a fragmentary sectional view taken on the line 6-6 of Figure 5 showing the circuit for the turn table motor open;

Figure 7 is an enlarged fragmentary view of the latch;

Figure 8 is an elevational view taken in the direction of the arrow 8 of Figure 5 with the parts in the position shown in full lines in Figure 5;

Figure 9 is a sectional view showing the contacts arranged for controlling an auxiliary motor which actuates a repeat or automatic record change mechanism, the parts being shown in the position shown in Figure 5;

Figure 10 is a top plan view of a form of automatic stop adapted for use with spring motor phonographs, parts being shown in section below the table of the phonograph;

Figure 11 is a sectional view taken on the line 11-11 of Figure 10.

While the automatic control contemplated by the present invention may be used on various forms of sound reproducing machines, it is for convenience here shown as being used with a conventional phonograph having a turn table 10, tone arm 11, reproducer 12 and stylus 13. The device, however, may be used with other forms of phonograph records and with electric pick up devices. The tone arm 11, which acts as a swinging arm to support the reproducing means, is pivoted to swing about an axis 14 and carries with it a short arm 15 which may, as here shown, be placed above the table 16 of the phonograph.

If the arm is placed above the table, it is provided with a downwardly bent end 17 which passes through a slot 18 in the table. The remaining parts of the control device are placed underneath the table 16 as indicated in dotted lines in Figure 1.

The swinging arm 17 carried by the supporting arm and reproducing means is cooperatively associated with a movable member 20 so that this member may move with the tone arm during the latter part of the playing of a record. In the form of invention herein shown the member 20 is in the form of a long flat arm pivoted at 21 on a suitable support 22 and slideable along a guide 22'. The form of connection provided between the parts 17 and 20 includes a slot 23 carried in a lateral extension 24 on the arm 20. This slot is so arranged that the front end of the slot is engaged by the extension 17 of the arm 15 during the playing of the latter part of the record so as to be carried in a clockwise direction by the stylus as it traverses the record grooves, and at a speed determined by the pitch of the sound groove.

A second movable member is here shown in the form of a long, thin, flat arm 25, which extends alongside the arm 20. It is pivoted to the arm 20 at 26 and an expansion spring 27 interposed by these arms acts to hold them separated in the position shown in full lines. The distance that they can separate, however, is limited by means of a cross strap 28 fastened to the arm 25 and hooked over a pin 29 on the arm 20. This arrangement of parts permits the arms 20 and 25 to swing bodily as a unit about the pivot 20 when the pin 17 reaches the end of the slot 23. There is, however, nothing to prevent moving the arm 20 toward the arm 25 when that arm is held stationary or compelled to move at a rate slower than the movement produced by the advance of the tone arm.

One of the many forms of mechanism for maintaining the advance of the arm 25 at the same rate that the arm 20 is moved by the stylus is shown in the drawings, and will now be described. The arm 25 pivotally supports two members 30 and 31 cooperatively associated for the purpose above referred to. The member 31 which acts as a trigger or detent is pivoted on arm 25 at 32. It carries a long arm 33 which is adjacent the end 34 of the swinging arm 20. The detent arm 31 also is provided with a short arm 35 which carries a downwardly extending pin 36 to cooperate with a notch 37 in the adjacent end 38 of the member 30. The member 30 is pivoted at 39, and besides being provided with the notched end 38 for the pin 36, it also carries a downwardly extending portion 40, serrated as shown at 41, to cooperate with a worm 42 driven at a constant speed by the turn table motor. In order to hold the pin

36 in the notch 37, a spring 43 is provided between the movable member 25 and the left end 44 of the member 30.

In the form of construction illustrated in Figures 1 to 8, inclusive, the arm 25 is provided with laterally extending contact carrier 45 which may conveniently be in the form of a strip of insulating material. The lower end 46 of this extension carries two spring contact members 47 and 48 shown more clearly in Figures 3 and 6. These spring contact members are in contact when the parts are in the position shown in Figures 2 and 3 and are connected to the phonograph motor M by leads 50 and 51 so that the turn table motor is operated. The arm 44 of the member 30 is provided with wedge shaped insulating member 52 for the purpose to be described.

Assuming that the parts are in the position shown in Figure 2 and that the phonograph is in operation, the movement of the parts will be as follows: During the playing of the latter part of the record, the arms 20 and 25 and all the parts carried by them will move in a clockwise direction as a unit pivoting about the center 21. The worm 42 is continuously revolving being driven by the phonograph motor and soon the serrated edge 41 of the locked member 30 will engage with the threads of the worm. This engagement will take place when the stylus is at a predetermined distance from the center of the record, which may conveniently be such that about one-quarter to three-eighths of an inch of playing surface is yet to be played. As the interlocked members 30 and 31 are both carried on the arm 25 these three members and parts connected to them may move about the pivot 26. As soon as the serrated edge engages the worm, it will be apparent that the arm 25 and these parts carried by it will be moved at a speed determined by the worm. As the parts are preferably so proportioned that the speed of the part 25 when driven by the worm is the same as the speed which it had when being moved by the stylus, there will be no relative movement of the parts 20 and 25. In other words, they will maintain the same spacing which they formerly had and all the parts will move in a clockwise direction as indicated in the dot and dash lines of Figure 2. In order to insure that the device will function the same on all records which have approximately the same pitch, the worm is geared to run at a speed corresponding to the record having the least grooves per inch. This will cause the worm to move both arms 20 and 25, taking the drive for arm 20 away from the extension 17. This extension, however, will trail the arm so closely that subsequent operations will be carried out properly.

When, however, the stylus moves out of the sound grooves into the special control groove, it must as above pointed out, move at a higher rate owing to the increased pitch of this por-

tion of the sound groove. While this movement may take place in a portion of the revolution, it will be obvious that this movement will bring the tip 34 of the arm 20 over toward the tip 33 of the detent arm 31 as shown in Figure 4. As the arm 25 and parts carried by it are now under the control of the worm 42, it will be apparent that these parts can not be bodily removed by the engagement of the parts 34 and 33 and hence the pressure applied by the arm 34 against the arm 33 will turn the detent arm in a clockwise direction about the pivot 32 thereby releasing the pin 36 from the notch 37 and permitting the spring 43 to swing the member 31 about the pivot 39. This will shift the parts from the dot and dash line position of Figure 2 to the full line position of Figure 5.

Referring now to Figures 5, 6 and 8, it will be noted that the serrated edge 41 of the member 30 has been released from the worm 42 and that the spring 43 has forced the insulating member 52 in between the contacts 47 and 48 thereby opening the circuit for the turn table motor M and stopping it.

To reset the control mechanism and close the motor circuit, it is merely necessary to swing the parts back to the dot and dash line position of Figure 5. In the form of construction here shown, this movement will be accomplished by swinging the tone arm back toward the position for commencing the playing of a record. During this return movement of the tone arm, the extension 17 moves back to the upper end of the slot 23 and then moves the parts to the dot and dash lines shown in this figure. During this movement, the arms 20 and 25 bodily move as a unit. A resetting link 53 is carried by a pin 54 extending upwardly from an arm 55 of detent 31. The link 53 is slotted as shown at 56 and is carried on a pin 57 carried on a link 20. It is brought against a stationary abutment 58. A continued movement of the tone arm will cause the detent member 31 to turn about its axis 32 bringing the pin 36 against the edge 59 of the member 30 causing it to swing about its axis until the pin 36 enters the notch 37, at which time the detent mechanism will be again locked in the position indicated in Figure 2. The switch for the phonograph motor M will now be closed and the motor will again start in operation.

If desired, a limit stop may be conveniently arranged to cooperate with the form of mechanism above described. This limit stop may take the form of a stationary cam member 60 mounted in a position to be engaged by a pin 61 carried on the arm 35 of the detent member 31. It will be in such a position that the movement of the tone arm in a clockwise direction beyond a predetermined amount will bring the pin 61 against the cam 60. This will cause a clockwise movement

of the detent 31 about the pivot 32 releasing 65 the locked member 30.

This limit stop also operates to insure the functioning of the control mechanism after the completion of the playing of records not provided with a control groove or wherein 70 the groove leading into the control groove is too low in pitch or worn so the stylus refuses to follow it. In cases such as these the worm 42 will continue to move the arm 25 and parts carried thereby inwardly, carrying 75 the arm 20 along with it. After a short time, these parts will pass beyond the dot and dash line position of Figure 2 to bring the pin 61 against the cam 60 thereby releasing the locked member 30. This insures that the 80 control device functions within a predetermined time after the stylus has brought the tone arm past a point at which the worm assumes the drive of part of the control device.

A manually operable device for stopping 85 the motor at any time even though the playing of the record has not been completed is indicated in Figures 1 and 8. It is suitably mounted on the underside of the table 16 of the phonograph. As here shown, a length of 90 flexible steel wire 62 is mounted to swing about a support 63 connected to an accessible knob 64 on top of the phonograph table. The parts are so arranged that the tip of the wire 62 may engage the upwardly extending pin 54 to strike it a light blow when the knob 64 is turned in a clockwise direction. The engagement of the part 62 with this pin 95 54 will break the toggle connection and release the parts so that the spring 43 may 100 actuate the same and open the motor switch. The wire 62 is flexible enough so that the continued movement of the knob 55 will permit it to pass by the part 54.

The structure which has been shown in 105 Figures 1 to 8, inclusive, and described in detail, is one which is intended for use with an electric phonograph having an electrically operated turn table motor and operating to stop the motor at the completion of the playing of a record. The present form of automatic control mechanism, is, however, suitable for automatically controlling an auxiliary motor used in an automatic repeating or record changing phonograph. The only 110 changes necessary in the structure of the parts shown in Figures 1 to 8, inclusive, is, to rearrange the contact mechanism. Instead of providing normally closed contacts such as 115 shown at 47 and 48 in Figure 2, and opening 120 these contacts by means of an insulating member 52, the control device will now be provided with normally opened contacts 47' and 48' as indicated in Figure 9 and instead of using an insulating member between the contacts, the device will now be provided with a conducting plate 52' insulatively carried 125 on the arm 44 of the member 30. With this

form of construction the auxiliary motor M' will be started when the parts are tripped as shown in the full line position of Figure 5 and will continue to run until the mechanism 5 is reset. It is of course contemplated that auxiliary switch mechanism would be used for controlling the motor M' in case it was desired to have it operate when the switch contacts 47' and 48' were electrically disconnected.

Reference is now made to Figures 10 and 11 which illustrate a form of automatic stop suitable for use with phonographs having spring motors. Corresponding reference characters 15 are applied to these figures for parts which may be the same as those previously described in detail.

A tripping arm 70 is hingedly mounted at 71 on the member 25 and overlies the arm 44' 20 of the member 30. The arms 20 and 25 and all parts carried by the same operate in the same manner as has been previously described so that the member 30 is released upon the completion of the playing of a record (or 25 upon engagement with the limit stop, or operation of the rejecting device), whereupon the spring 43 throws this lever in a counter clockwise direction. As will be clear from Figure 10, the movement of the member 30 will cause 30 the tripping arm 70 to be swung upwardly on its pivot.

Suitable brake mechanism is mounted on the under side of the phonograph table 16. As here shown this brake mechanism includes 35 a friction member 72 adapted to engage the side of the turn table 10. This friction member is carried on a bell crank 73 pivoted at 74 on a bracket 75 and connected by means of a link 76 with a lever 77. The left hand end 78 of the lever 77 is cooperably engaged with a locking dog 79 held against it by means of a spring 80. The locking dog 78 is in the form 40 of a bell crank lever having a long, lower arm 81 overlying the tripping member or arm 70 which is normally out of contact with it.

During the playing of a record the mechanism carried on the pivot 21 will move clockwise a sufficient amount to bring the tripping member 70 underneath the arm 81 of the 45 detent member 79. The camming action of the member 30 against the tripping member 70 will cause this member to press upwardly on the underside of the bell crank 81 thereby tensioning the spring 80 and moving the detent away from the lever 77, whereupon a spring 82 will force the brake shoe over against the side of the turn table. The parts of the automatic stop mechanism carried on the pivot 21 may be reset in the same manner as has been previously described. This 50 resetting, however, does not effect the resetting of the brake mechanism which must be done manually by pressing the parts back to the position indicated in the drawing, whereupon the spring 80 brings the detent under-

neath the end of the lever 77 and locks the brake shoe out of position, permitting the spring motor to start rotating the record tablet.

It will be noted that in the form of construction illustrated in Figures 10 and 11, the release of the brake shoe mechanism is accomplished without any tendency to swing the members pivoted about the center 21 on their vertical axes. This is of considerable 70 importance because these members are so light in weight that they would easily swing on the pivot 21 if any attempt were made to develop pressure in a horizontal plane. The sole reaction on these pivoted parts is in a vertical 75 direction which is easily taken care of in the supports for the member 20 with no tendency to turn the member 20 on its pivot.

Where it is desired to utilize the present 80 form of automatic control mechanism in a record changing mechanism or in an automatic repeating phonograph wherein these 85 record changing and automatic repeating functions derive power from the same motor that operates the turn table, it will be obvious that one can utilize a trip mechanism of the form shown in Figures 10 and 11 for shifting a suitably located clutch which couples the phonograph motor to the 90 record change and repeat mechanism.

It is obvious that the invention may be embodied in many forms and constructions, and I wish it to be understood that the particular 95 forms shown, are but a few of the many forms. Various modifications and changes being possible, I do not limit myself in any way with respect thereto.

I claim:

1. The combination with a talking machine having a rotatable record support, a driving motor for the record support, and sound reproducing means including a stylus cooperative with sound grooves on the sound record and moved thereby across said support, of a control device automatically brought into operation upon the movement of the reproducing means toward the center of the record support at a speed greater than the normal speed of approach brought about by the sound grooves, said device including a member controlled directly by the reproducing means and a second member operating at a predetermined speed relative to the speed of the record support and interconnected with the first member to function the 110 control device.

2. The combination with a talking machine having a rotatable record support, an electric motor for driving the record support, and sound reproducing means including a stylus cooperative with sound grooves on the sound record and moved thereby across said support, of a switch in the motor circuit which opens automatically in response to a movement of the reproducing 125 130

means toward the center of the record support at a speed greater than the normal speed of approach brought about by the sound grooves, and operating means for said switch, 5 said means including a member controlled directly by the reproducing means and a second member operating at a predetermined speed relative to the speed of the record support and interconnected with the first member 10 to function the switch.

3. The combination with a talking machine having a rotatable record support, a driving motor for the record support, and sound reproducing means including a stylus 15 cooperative with sound grooves on the sound record and moved thereby across said support, of a control device automatically brought into operation upon the movement of the reproducing means toward the center 20 of the record support at a speed greater than the normal speed of approach brought about by the sound grooves, said device including two members operable simultaneously by the reproducing means during a portion of the 25 movement thereof, motor operated driving means for thereafter assuming the drive of one of said members without substantial change in speed whereby differential action between said members is brought about by said increased speed, and mechanism responsive to said differential action for functioning said control device.

4. The combination with a talking machine having a rotatable record support, an 35 electric motor for driving the record support, and sound reproducing means including a stylus cooperative with sound grooves on the sound record and moved thereby across said support, of a switch in the motor circuit which opens automatically in response to a movement of the reproducing means toward the center of the record support at a speed greater than the normal speed of approach brought about by the 45 sound grooves, and operating means for said switch, said means including two members operable simultaneously by the reproducing means during a portion of the movement thereof, motor operated driving means for thereafter assuming the drive of one of said members without substantial change in speed whereby differential action between said members is brought about by said increased speed.

5. The combination with a talking machine having a rotatable record support, a driving motor for the record support, and sound reproducing means including a stylus 60 cooperative with sound grooves on the sound record and moved thereby across said support, of a rotatable member actuated by the motor at a speed proportional to the speed of the record support, a stylus actuated member movable at a speed dependent upon the 65 pitch of the record groove, an intermediate

member movable by the stylus actuated member throughout a predetermined range of movement thereof and into a position whereupon it is actuated by the rotatable member at uniform speed, and mechanism 70 responsive to differential action between the stylus actuated member and the intermediate member for operating a phonograph control device.

6. The combination with a talking machine having a rotatable record support, a driving motor for the record support, and sound reproducing means including a stylus cooperative with sound grooves on the sound record and moved thereby across said support, of a worm actuated by the motor at a speed proportional to the speed of the record support, an arm actuated by the stylus at a speed dependent upon the pitch of the record groove, a second arm movably carried by the first arm and movable therewith, a toothed member carried by the second arm and engageable with the worm when the stylus has actuated the first arm to a predetermined position, whereupon the worm 90 may continue the movement of the second arm at the same speed, and mechanism responsive to differential action between the two arms for actuating a phonograph control device.

7. The combination with a talking machine having a rotatable record support, a driving motor for the record support, and sound reproducing means including a stylus cooperative with sound grooves on the sound record 100 and moved thereby across said support, of an arm actuated by the stylus at a speed proportional to the pitch of the record groove, a second arm pivotally carried by the first arm and normally having a fixed position relative thereto, a motor driven worm adjacent the second arm, and a follower for the worm carried by the second arm and engageable with the worm to actuate the arm at the same speed it is normally moved by the stylus actuated arm whereby the arms move in unison so long as the record groove has uniform pitch and a differential movement of the arms is brought about by a variation of pitch of the record groove.

8. The combination with a talking machine having a rotatable record support, a driving motor for the record support, and sound reproducing means including a stylus cooperative with sound grooves on the sound record 120 and moved thereby across said support, of an arm actuated by the stylus at a speed proportional to the pitch of the record groove, a second arm pivotally carried by the first arm and normally having a fixed position relative thereto, a motor driven worm adjacent the second arm, a follower for the worm pivotally carried by the second arm and a detent for locking the follower in position to become engageable with the worm to actuate the arm 130

- at the same speed it is normally moved by the stylus actuated arm whereby the arms move in unison so long as the record groove has uniform pitch and a differential movement of the arms is brought about by a variation of pitch of the record groove, the detent being disengaged upon said differential movement. 5
9. The combination with a talking machine having a rotatable record support, a driving motor for the record support, and sound reproducing means including a stylus cooperative with sound grooves on the sound record and moved thereby across said support; of an arm actuated by the stylus at a speed proportional to the pitch of the record groove, a second arm pivotally carried by the first arm and normally having a fixed position relative thereto, a motor driven worm adjacent the second arm, a follower for the worm carried by the second arm and engageable with the worm to actuate the arm at the same speed it is normally moved by the stylus actuated arm whereby the arms move in unison so long as the record groove has uniform pitch and a differential movement of the arms is brought about by a variation of pitch of the record groove, and mechanism responsive to said differential movement for actuating a phonograph control device. 20
- 25 10. The combination with a talking machine having a rotatable record support, a driving motor for the record support, and sound reproducing means including a stylus cooperative with sound grooves on the sound record and moved thereby across said support, of an arm actuated by the stylus at a speed proportional to the pitch of the record groove, a second arm pivotally carried by the first arm and normally having a fixed position relative thereto, a motor driven worm adjacent the second arm, a follower for the worm to actuate the arm at the same speed it is normally moved by the stylus actuated arm whereby the arms move in unison so long as the record groove has uniform pitch and a differential movement of the arms is brought about by a variation of pitch of the record, and phonograph controlling trigger mechanism mounted on the second arm, said trigger mechanism being released by a sudden movement of the first arm. 45
- 50 11. The combination with a talking machine having a rotatable record support, a driving motor for the record support, and sound reproducing means including a stylus cooperative with sound grooves on the sound record and moved thereby across said support, of an arm actuated by the stylus at a speed proportional to the pitch of the record groove, a second arm pivotally carried by the first arm and normally having a fixed position relative thereto, a motor driven worm adjacent the second arm, a follower for the worm to actuate the arm at the same speed it is normally moved by the stylus actuated
- arm whereby the arms move in unison so long as the record groove has uniform pitch and a differential movement of the arms is brought about by a variation of pitch of the record groove, phonograph controlling trigger mechanism mounted on the second arm, said trigger mechanism being released by a sudden movement of the first arm, and means to reset the trigger mechanism when the arms are swung backward to restore the reproducing means to starting position. 70
- 75 12. In a phonograph, the combination with a motor driven turntable, a record, and a movable arm carrying a reproducer and stylus, the record having a grooved playing surface and a groove which suddenly moves the arm inwardly after the completion of the playing of a record, of phonograph control mechanism sensitive to such sudden inward movement of the arm whereby the mechanism will function only after the completion of the playing of a record. 80
- 85 13. In a phonograph the combination with a motor driven turntable, a record, and a movable arm carrying a reproducer and stylus, the record having a grooved playing surface and a groove which suddenly moves the arm inwardly after the completion of the playing of a record, of phonograph control mechanism sensitive to such sudden inward movement of the arm whereby the mechanism will function only after the completion of the playing of a record, said mechanism including a lost motion connection with the arm to render it inactive when the arm is beyond a predetermined distance from the center of the record. 90
- 95 14. In a phonograph the combination with a motor driven turntable, a record, and a movable arm carrying a reproducer and stylus, the record having a grooved playing surface and a groove which suddenly moves the arm inwardly after the completion of the playing of a record, of a switch in the motor circuit and switch operating mechanism sensitive to such sudden inward movement of the arm whereby the mechanism will function only after the completion of the playing of a record. 100
- 105 15. In a phonograph the combination with a movable arm, a stylus on the end of the arm, a rotating turn table, and a disk record on the turn table, said record having a playing surface for cooperation with the stylus and a groove inside the playing surface into which the stylus passes after completion of the playing of a record, a portion of said groove having a substantially greater pitch than the grooves of the playing surface, of phonograph control mechanism, and means for setting said phonograph control mechanism into operation in response to the accelerated movement of the arm brought about by the portion of the groove of greater pitch. 110
- 120 16. In a phonograph, the combination with a movable arm, a stylus on the end of the arm, 125

a motor driven turn table, and a disk record on the turn table, said record having a playing surface for cooperation with the stylus and a groove inside the playing surface into which the stylus passes after completion of playing of the record, a portion of said groove having a substantially greater pitch than the grooves of the playing surface, of a switch in the motor circuit, switch control mechanism, and means for operating the switch control mechanism in response to the accelerated movement of the arm brought about by the portion of the groove of greater pitch.

17. In a phonograph, a disk record having a playing surface and a control groove inside the playing surface to receive the stylus after completion of the playing of the record, a portion of said control groove being of greater pitch than the grooves of the playing surface, and a phonograph control device set into operation while the stylus is traversing the said portion of greater pitch.

18. In a phonograph, a disk record having a playing surface and a control groove inside the playing surface to receive the stylus after completion of playing of the record, a portion of said control groove being of greater pitch than the grooves of the playing surface, a driving motor for the phonograph, a motor control switch, and means to open the switch when the stylus is traversing the said portion of greater pitch.

19. In a phonograph, a record having a playing surface and a control groove into which the stylus passes after completion of the playing of the record, a portion of said control groove being of greater pitch than the grooves of the playing surface, and a phonograph control device set into operation while the stylus is traversing the said portion of greater pitch, said control device being unaffected by subsequent changes of the pitch of the groove.

20. In a phonograph, a disk record having a playing surface and an eccentrically located control groove inside the playing surface to receive the stylus after completion of the playing of the record, one half of said control groove being of greater pitch than the grooves of the playing surface, and a phonograph control device set into operation while the stylus is traversing the first half of said eccentric groove, said device being unaffected by the return movement of the stylus in the second half of the groove.

21. In a phonograph, the combination with an automatic control device responsive to the sudden movement of the phonograph tone arm brought about by the stylus entering a groove of higher pitch than the pitch of the sound grooves, of a manually operable member for releasing the automatic control device.

22. In a phonograph, the combination with an automatic control device responsive to the

sudden movement of the phonograph tone arm brought about by the stylus entering a groove of higher pitch than the pitch of the sound grooves, of a fixed limit stop against which the control device is brought when the tone arm is within a predetermined distance of the center of the turn table, said limit stop releasing the automatic control device.

23. A phonograph having a stylus actuated movable arm, a motor operated worm, a second arm carried on the first arm, a switch element fixedly carried by the second arm, a circuit controlling lever movably carried by the second arm, a spring urging the lever toward the switch element, a detent carried by said second arm for locking the lever out of engagement with the other switch element, and a follower for the worm supported from the second arm so that the second arm may be actuated by the worm when the follower is in engagement with the worm, the detent being engageable with the first arm to release the lever.

24. A phonograph having a stylus actuated movable arm, a motor operated worm, a member movably carried by the movable arm and supporting two pivoted members one of which is a detent member for locking the other in a predetermined position against the tension of a spring, said other member engaging the worm during a predetermined range of movement of the arm and being driven thereby, the detent member being engageable with the movable arm upon an accelerated movement thereof to release the locked member and permit the spring to release it from the worm so that all the parts may move free of the worm.

25. A phonograph having a stylus actuated movable arm, a motor operated worm, a member movably carried by the movable arm and supporting two pivoted members one of which is a detent member for locking the other in a predetermined position against the tension of a spring, said other member engaging the worm during a predetermined range of movement of the arm and being driven thereby, the detent member being engageable with the movable arm upon an accelerated movement thereof to release the locked member and permit the spring to release it from the worm so that all the parts may move free of the worm, and means for resetting the detent into locking position when the arm returns the swinging arm.

26. In a phonograph, a swinging support for a sound reproducing means, a swinging arm having a lost motion driving connection with the swinging support for moving the swinging arm with the swinging support during predetermined portions of its movement, a second member movably carried by the swinging arm and carrying thereon a spring pressed lever and a detent lever cooperative

therewith to lock it in a predetermined position, means to unlock the spring pressed lever, and means to stop the phonograph when said lever is released.

5 27. In a phonograph, a swinging support for a sound reproducing means, a swinging arm having a lost motion driving connection with the swinging support for moving the swinging arm with the swinging support 10 during predetermined portions of its movement, a second member movably carried by the swinging arm and carrying thereon a spring pressed lever and a detent lever cooperative therewith to lock it in a predetermined position, means to unlock the spring 15 pressed lever to stop the phonograph when said lever is released, and means for resetting the levers when the swinging support is moved to one of its extreme positions.

28. In the control of phonographs, the method which consists in actuating two members from one power source at a speed proportional to the normal feed of the sound 25 reproducing means of the phonograph, then changing the power drive for one member to another source which actuates it at the same speed, and then actuating the other member at a speed in excess of the normal 30 speed to effect a differential movement between the members, and releasing a third member which frees a control device.

29. In the control of phonographs, the method which consists in simultaneously actuating two arms from one power source at a speed proportional to the normal feed of the sound reproducing means of the phonograph, then changing the power drive for one of the arms to another source which actuates it at the same speed, and then actuating the other arm at a speed in excess of the normal speed to effect a differential movement between the arms, and releasing a third member which frees a control device.

45 30. The step in the method of operating controls for phonographs which consists in bringing about a differential movement between two members one of which moves at a predetermined speed relative to the normal movement of the stylus and a second member which follows the movements of the stylus.

31. In a phonograph, the combination with a motor driven record support, a record, a 55 movable arm carrying a reproducer and stylus, the record having a grooved playing surface cooperative with the stylus, a motor driven member actuated at a speed proportional to the speed of the record support, a two part control device, both parts of 60 which are actuated by the movable arm until the stylus brings one of said parts into cooperative relation with the motor driven member whereupon both parts are actuated 65 by their respective drivers at the same speed

so long as the stylus is in a record groove, and a stop against which the motor driven member brings one of said parts after a predetermined number of revolutions of the record support.

70 32. In a phonograph, the combination with a motor driven record support, a record, a movable arm carrying a reproducer and stylus, the record having a grooved playing surface cooperative with the stylus, a control device bodily movable with the stylus, a motor operated member moving at a speed proportional to the speed of the record support and against which the control device is brought by the movement of the stylus whereupon the 80 motor operated member acts to move the control device in the same direction and at the same speed, and a stop against which the control device is brought after a predetermined number of revolutions of the record 85 support.

33. The combination with a talking machine having a rotatable record support, a driving motor for the record support, and sound reproducing means including a stylus 90 cooperative with sound grooves on the sound record and moved thereby across said support, of a worm actuated by the motor at a speed proportional to the speed of the record support, an arm actuated by the stylus at a 95 speed dependent upon the pitch of the record groove, a second arm movably carried by the first arm and movable therewith, a toothed member carried by the second arm and engageable with the worm when the stylus has 100 actuated the first arm to a predetermined position, whereupon the worm may continue the movement of the second arm at the same speed, a stop against which the second arm is brought after a predetermined number of 105 revolutions of the record support, and a phonograph control device actuated when said stop is engaged.

34. A phonograph control device comprising a swinging arm adapted to be normally moved by the stylus during the playing of a record, a second arm bodily carried thereby and having limited freedom of movement relative thereto, an electric switch carried by the second arm, normally set trigger mechanism carried by the second arm, the switch being open or closed according to the position of the trigger mechanism, and means to break the setting of the trigger mechanism when the first arm is brought too close to the second arm.

110 35. A phonograph control device comprising a swinging arm adapted to be normally moved by the stylus during the playing of a record, a second arm bodily carried thereby 115 and having limited freedom of movement relative thereto, an electric switch carried by the second arm, normally set trigger mechanism carried by the second arm, the switch being open or closed according to the position 120 125 130

of the trigger mechanism, and a fixed stop in the path of the trigger mechanism and acting to break the setting thereof when the arms are carried beyond a predetermined point.

- 5 36. A phonograph control device comprising a swinging arm adapted to be normally moved by the stylus during the playing of a record, a second arm bodily carried thereby and having limited freedom of movement
10 relative thereto, a worm driven at a speed proportional to record speed, an electric switch carried by the second arm, the switch being open or closed according to the position of the trigger mechanism, one member
15 of said trigger mechanism carrying a follower for the worm adapted to move the second arm at the same speed that the stylus moves the first arm whereby the spacing of the arms is maintained while the stylus is in the sound
20 groove, and means for breaking the setting of the trigger mechanism when the first arm is suddenly moved toward the second arm.
37. A phonograph control device comprising a swinging arm adapted to be normally moved by the stylus during the playing of a record, a second arm bodily carried thereby and having limited freedom of movement

relative thereto, a worm driven at a speed proportional to record speed, an electric switch carried by the second arm, the switch 30 being open or closed according to the position of the trigger mechanism, one member of said trigger mechanism carrying a follower for the worm adapted to move the second arm at the same speed that the stylus moves 35 the first arm whereby the spacing of the arms is maintained while the stylus is in the sound groove, and a fixed stop in the path of the trigger mechanism and acting to break the setting thereof when the worm carries the 40 arms to a predetermined position.

38. In a phonograph, a record having a playing surface and a control groove into which the stylus passes after completion of the playing of the record, a portion of said 45 control groove being of greater pitch than the grooves of the playing surface, and a phonograph control device set into operation while the stylus is traversing the said portion of greater pitch. 50

Signed at New York, county of New York, and State of New York, this 31st day of October, 1927.

JACK POTTER STOCKTON.
